UNITED STATES PATENT OFFICE.

NICOLA D'AGOSTINO, OF LOS ANGELES, CALIFORNIA, ASSIGNOR OF ONE-THIRD
TO ANTONIO BIZZARRI AND ONE-THIRD TO RAPHAEL RAULLI, BOTH OF LOS
ANGELES, CALIFORNIA.

DRYING-ROOM FOR CEREAL PASTES.

1,244,429.

Specification of Letters Patent. Patented Oct. 23, 1917.

Application filed September 5, 1916. Serial No. 118,424.

To all whom it may concern:

Be it known that I, NICOLA D'AGOSTINO, a citizen of the United States, residing at Los Angeles, in the county of Los Angeles and 5 State of California, have invented new and useful Improvements in Drying-Rooms for Cereal Pastes, of which the following is a specification.

This invention relates to a drying room 10 especially suited for cereal pastes such as macaroni, spaghetti, vermicelli and the like.

In the drying of cereal pastes it is desirable to effect a uniform drying not too quickly and not too slowly. A quick drying 15 causes a brittle product with a very low moisture content which is not desirable. A slow drying may result in fermentation or souring and in a distortion of the product due to its own weight while in a plastic state.

20 It is an object of my invention to provide a device in which uniform drying is effected and which may be regulated so as to prevent souring.

In addition to the broader features of my 25 invention there are certain specific features of design which secure simplicity of structure and ease of operation.

I have illustrated embodiments of my invention in the accompanying drawing, in 30 which:

Figure 1 is a perspective view of the preferred form of my drier with portions of the walls broken away to better show the interior.

35 Fig. 2 is a transverse section of the structure shown in Fig. 1.

Fig. 3 is a section as seen on the line 3—3 of Fig. 2.

Fig. 4 is a transverse section of a modified 40 form.

Fig. 5 is a section as seen on the line 5—5 of Fig. 4.

Fig. 6 is a transverse section of a further modified form.

45 Fig. 7 is a section as seen on the line 7—7 of Fig. 6, and

Fig. 8 is a transverse section of a still further modification.

Referring particularly to Figs. 1, 2 and 50 3, a housing is indicated by 9 and forms a substantially closed casing. The casing is divided by a vertical wall 10 into two compartments, and the wall 10 is spaced from the bottom of the casing to provide an open-

ing which establishes communication between a fan compartment 11 and a drying compartment 12. Regulating means is provided at the top of the drying compartment and consists of an opening 13 and doors 14 which may be adjusted to vary the outlet of 60 opening 13. In addition to the opening 13, openings 15 are provided which extend the length of the casing and are continuously open. Upon the wall 10 within the drying compartment 12 and upon the wall of the 65 casing opposite thereto are cleats 16 which serve as supports for macaroni or spaghetti racks. A foot board 17 is placed in compartment 12 upon which the workmen may stand while placing the paste in position to be 70 dried. Foot board 17 is also arranged so that it may be tilted as particularly shown by the dotted lines in Fig. 2, thereby regulating the area for the flow of air into compartment 12.

75 Within compartment 11 and extending longitudinally thereof is a rotatable shaft 18 upon which are mounted fans 19 and 20. A pulley 21 is mounted upon the outside of the casing and is arranged for driving the 80 fans.

The operation of the construction just described is found to be such that upon rotation of the fans air surges back and forth from the fan compartment to the drier compartment. This operation is probably due to the creation of pressure in compartment 11 and forcing of air into compartment 12 until the air pressure in compartment 11 has been reduced as compared with that in drier 90 compartment 12. There is then a surge of air from compartment 12 to compartment 11, and air is again forced by the fans back into compartment 12.

95 It will be noted that fans 19 and 20 are directed to force air toward one another. This arrangement of fans is efficient for creating the surging, and for a uniform distribution of air. It is also found that surging of the air from one compartment to the 100 other is most effective in producing a properly dried paste. To prevent souring the air must be changed in the compartments, and the amount of air discharged and admitted must be regulated depending upon the particular character of the paste being dried, and upon the amount of drying which has all ready been accomplished. This is 105

effected by adjusting the doors 14 and further adjustment may be secured by means of the foot board 17. A door 22 is provided at one end of the casing for ingress and egress to the drying room. It is also found advantageous to place a deflector 23 to direct air from one compartment to the other. This deflector consists of a curved wall which is placed in the casing.

10 Referring to Figs. 4 and 5 a casing 24 is divided by a transverse horizontal partition 25, one end thereof spaced from the end wall of the casing to leave an opening 26 for communication of the fan compartment 27 and the drier compartment 28. In the drier compartment is an opening 29 having a hinged door therefor to adjust the size of the opening. In the fan compartment 27 is a horizontally disposed shaft 30 upon which 20 are mounted two oppositely disposed fans 31 and 32. Upon the end of shaft 30 is a pulley 33 for driving the fans. A deflector 31' is arranged to direct the air from compartment 27 to compartment 28. The 25 modified form of drier just described is adapted for drying of vermicelli and cereal pastes of a like character wherein it is necessary to support them upon trays 34. The operation of the structure is the same as that 30 described in the preferred form.

Referring to Figs. 6 and 7, a casing 35 is provided with a transverse horizontal partition 36 and a deflector 37, thereby producing a drier and fan compartment like 35 that shown in Fig. 4. A hinged door 38 controls the opening to the atmosphere. The structure just described differs from that shown in Figs. 4 and 5 in having a single fan 39 mounted upon a shaft 40 which 40 is disposed transverse to the casing. The drier compartment may be used for macaroni or for trays containing other cereal pastes.

Fig. 8 illustrates a structure in which a 45 single set of fans 42 is used to circulate air in two drying compartments. The casing 43 is constructed with vertical partition walls 44 and 45 which are parallel to each other and spaced from the top and bottom 50 walls of the casing to provide communication with drier compartments one at each side of the casing. Doors 46 and 47 control openings to regulate the drying of macaroni or like cereal pastes which are 55 disposed upon racks in the drying compartment. Deflectors 48 and 49 are also provided to direct air to the drying compartments.

What I claim is:

60 1. A drier of the class described, comprising a substantially closed housing divided into compartments communicating through a single opening, one of said compartments adapted to contain the material 65 to be dried, the other of said compartments

being entirely closed except for said opening; and a blower in the other compartment.

2. A drier of the class described, comprising a casing divided into compartments communicating through a single opening, one of said compartments adapted to contain the material to be dried and leaving an opening communicating with the outside of said casing, means for regulating said opening, the other of said compartments being entirely closed except for said opening, and a blower in the other compartment.

70 3. A drier of the class described, comprising a casing, a partition wall spaced from one side of said casing dividing the latter into a plurality of communicating compartments, one of said compartments being entirely closed except for the communicating opening, and a blower in one of said compartments, the other of said compartments adapted to contain material to be dried and provided with an opening communicating with the atmosphere.

75 4. A drier of the class described, comprising a substantially closed housing divided into communicating compartments, one of said compartments adapted to contain the material to be dried, a blower in another compartment, and a deflector for air to direct the air currents from one compartment 80 to another.

85 5. A drier of the class described, comprising a casing divided into communicating compartments, one of said compartments adapted to contain the material to be dried, an opening in said compartment communicating with the outside of said casing, means for regulating said opening, a blower in the other compartment, and a deflector for air to direct the air currents from one compartment 90 to another.

95 6. A drier of the class described, comprising a casing, a partition wall dividing the casing into two compartments and spaced from the casing wall at one end to form an 100 opening for establishing communication between said compartments, one of said compartments adapted to contain material to be dried, a blower in the other of said compartments comprised of two fans with their 105 planes of rotation parallel and normal to the plane of said opening.

110 7. A drier of the class described, comprising a casing, a partition wall dividing the casing into two compartments and spaced from the casing wall at one end to establish communication between said compartments, one of said compartments adapted to contain material to be dried, a blower in the other of said compartments comprised of two fans with their 115 planes of rotation parallel and normal to the plane of said opening, and a deflector to direct air from one compartment to the other.

120 8. A drier of the class described, comprising

ing a casing a partition wall spaced at one end from the bottom of said casing and dividing the latter into communicating compartments, a blower in one of said compartments, the other compartment adapted to contain material to be dried, and a foot board in the last named compartment disposed in the path of the current of air, and arranged to be tilted thereby forming a control for the flow of air.

9. A drier of the class described, comprising a casing, a partition wall spaced at one end from the bottom of said casing and dividing the latter into communicating com-

partments, a blower in one of said compartments, the other compartment adapted to contain material to be dried and having an opening to the atmosphere with means for regulating the same, and a foot board in the last named compartment disposed in the path of the current of air and arranged to be tilted thereby forming a control for the flow of air.

In witness that I claim the foregoing I have hereunto subscribed my name this 18th day of August, 1916.

NICOLA D'AGOSTINO.
